UNITED STATES PATENT OFFICE.

ANTHONY J. McCORMACK, OF NEW HAVEN, CONNECTICUT.

IRRIGATED BRUSH.

Application filed February 21, 1925. Serial No. 10,755.

To all whom it may concern:

Be it known that I, ANTHONY J. McCORMACK, a citizen of the United States, residing at New Haven, in the county of New Haven and State of Connecticut, have invented a new and useful Improvement in Irrigated Brushes; and I do hereby declare the following, when taken in connection with the accompanying drawings and the characters of reference marked thereon, to be a full, clear, and exact description of the same, and which said drawings constitute part of this application, and represent, in—

Fig. 1 a view in elevation of one form 15 which an irrigated brush, constructed in accordance with my invention, may assume, with the elastic rubber sleeve thereof partly in section.

Fig. 2 a view of the sleeve in central, longitudinal section on the line 2—2 of Fig. 1.

Fig. 3 a view thereof in transverse section on the line 3—3 of Fig. 1.

My invention relates to irrigated brushes, that is to say, brushes which are supplied 25 with water under pressure to facilitate their cleaning action, the object of my present invention being to provide an efficient brush of superior convenience in so far as it is designed to be slipped at pleasure on, over, or 30 off an ordinary hose-nozzle without removing any part thereof.

With these ends in view, my invention consists in an irrigated brush having an elastic rubber sleeve adapted in interior con- 35 formation to be slipped at pleasure on, over, or off a standard hose-nozzle, and also for the attachment to it of the ends of a brush into which water is discharged under pressure from the hose-nozzle.

My invention further consists in a brush 40 characterized as above and having the base-end of its soft rubber sleeve formed with an annular guard-flange for preventing the nozzle from contact with the surfaces being washed.

My invention further consists in an irrigated brush having certain details of construction as will be hereinafter described 45 and particularly pointed out in the claims.

In carrying out my invention, as herein shown, I employ a soft rubber sleeve 5 having a cylindrical chamber 6 formed near its brush-end with an inwardly-projecting, annular retaining-flange 7 and at its butt-end 55 with an annular outwardly-projecting guard-

flange 8. At opposite points upon the outside of the said sleeve it is formed with complementary, integral, molded ribs or offsets 9 parallel with the axis of the sleeve, extending nearly through the length thereof, and designed for the reception of the parallel ends 10 of the twisted loop-shaped wire-frame 11 of the brush proper 12, which, as shown, consists of bristles, but which may be replaced by tampico, yarn, strips of fabric, sponge, or any other of the several materials used in making brushes designed to be irrigated with water.

As shown, the brush-unit is loop-shaped or oval in form and has its center axis in line with the axis of the sleeve 5, but the brush will often be bent with respect to this axis.

It is designed that the soft rubber sleeve 5 shall be adapted in length, diameter and resiliency to be slipped or crowded on over a standard metal hose-nozzle such as 13 without removing any part thereof, as heretofore has been required, so that the brush may, at the pleasure of the owner, be slipped on and off the hose-nozzle as may be necessary without the use of any tools. When slipped or forced on over the hose-nozzle, its retaining-flange 7 is momentarily displaced, so as to permit the rim 14 at the end thereof to pass by it, after which the flange contracts and substantially resumes its normal shape, so as to hug the nozzle and retain the soft rubber sleeve 5 thereupon with a sufficient grip to hold it in place when the brush is being used.

It will be understood that the nozzle proper may be somewhat varied in size and design, and that many makes of such nozzles are on the market, but they are sufficiently standardized to enable my improved brush to be used with any one of them, due to the resiliency of the rubber entering into it.

When the brush is in place on the nozzle, the guard-flange 8 at its butt-end acts to 100 prevent the butt-end of the nozzle from making any contact with the surfaces being washed, this being particularly advantageous in washing automobiles, whereby their varnished and polished surfaces are guarded against being scratched.

I have spoken of the sleeve as being made of soft or resilient rubber, by which term I mean to cover any material having the same 105 general characteristics.

I claim:

1. The combination with a soft rubber sleeve, of a brush having a loop-shaped frame, having parallel, complementary ends embedded in the outer end of said sleeve at opposite points therein.
5
2. The combination with a soft rubber sleeve, said sleeve being provided at its outer end with an inwardly-projecting, integral, annular retaining-flange, of a brush having a loop-shaped frame, having parallel, complementary ends anchored in the outer end of the said sleeve.
10
3. The combination with a soft rubber sleeve, said sleeve being provided at its butt-end with an integral, annular, outwardly-

projecting guard-flange, of a brush having a loop-shaped frame, having parallel, complementary ends anchored in said sleeve at opposite points therein.

4. The combination with a soft rubber sleeve, formed at its outer end with an inwardly-projecting, integral, annular retaining-flange and at its butt-end with an integral, annular, outwardly-projecting guard-flange, of a brush having a loop-shaped frame, having parallel, complementary ends embedded in the outer end of said sleeve at opposite points therein.

In testimony whereof, I have signed this 30 specification.

ANTHONY J. McCORMACK.
